ELECTRIC OIL CONTROL VALVE

Roy W. Johnson, Milwaukee, Wis.

Application April 9, 1936, Serial No. 73,409

6 Claims. (Cl. 137—139)

This invention relates to an oil control valve regulated by the action of an electro-magnet which is energized or excited in response to a control instrumentality such as a room thermostat, a limit control or a pressure switch.

One of the objects of the invention is to provide an oil control valve of this character which is simple and compact in its construction, reliable in its operation, easy and comparatively inexpensive to manufacture and susceptible of ready installation. The valve is designed to provide a constant oil supply to a pot type burner on domestic heating installations, small process steam boilers, water heaters, and similar applications where a constant temperature must be maintained and where an electric circuit is available for control. It is of the high fire and low fire type.

In carrying out the present invention, the electric control unit is mounted on top of the valve body, and is protected by a tight fitting cover. When contact is made, either through a room thermostat, a limit control, or a pressure switch, the coil is energized which brings the armature forward. This armature in turn raises the sliding metering valve which allows the full capacity of the oil to pass to the burner. This is the high fire position. When de-energized, the armature swings away allowing the metering valve to drop to the low fire position. The control is made so that the high and low fire can be adjusted to individual needs. The high fire can be adjusted from full capacity down to almost nothing.

Other objects and advantages reside in certain novel features of the construction, arrangement and combination of parts which will be herein-after more fully described and particularly pointed out in the appended claims, reference being had to the accompanying drawing, forming a part of this specification, and in which:

Figure 1 is a view partly in side elevation and partly in longitudinal vertical section illustrating one construction in which the invention may be advantageously embodied;

Figure 2 is a view in transverse vertical section taken on line 2—2 of Figure 1; and

Figure 3 is a view in horizontal cross section taken on line 3—3 of Figure 1.

Referring to the drawing, it will be seen that in the embodiment of the invention there illustrated, a casing 1 is provided. Fuel is supplied to the casing 1 through an inlet 2 from a reservoir or other suitable source. Within the casing 1 there is a float controlled inlet valve 3 equipped with an automatic safety cut-off 4. This structure will not be described in detail as it per se

forms no part of the present invention and is fully described and claimed in my application filed March 3, 1933, Serial No. 659,448, for Devices for controlling the flow of fuel to oil burners and the like.

An outlet passage 5 is in direct communication with the main supply chamber 6 of the valve casing and is connected in any suitable way with the burner (not shown). A flanged sleeve 7 is fitted in the upper end of the outlet passage 5 and held in position by friction or otherwise. This sleeve 7 provides a valve seat for a tubular metering valve 8. The lower end of the valve is reduced as at 9 and the reduced portion 9 has a suitable number of metering slots 10 therein. At the juncture 15 of the reduced portion 9 and the main portion of the valve 8, a beveled shoulder 11 is provided and when the valve is fully closed seats against a correspondingly formed surface at the upper end of the valve seat 7.

In order that the outlet valve may be vented it is provided with an axial passage 12 extending down through its lower end and communicating at its upper end with a lateral port or opening 13 which communicates with the interior of the main supply chamber above the level of the liquid therein. A cover 14 is provided for the casing 1 and may be releasably secured in position in any suitable manner as, for example, by one or more screws 15.

The cover 14 is provided with an opening through which the upper part of the valve 8 extends. Associated with this opening is a short sleeve 16, which is fixed in position and for this purpose may be a separate piece secured to the cover 14 and also to a bracket 17 or, if desired, may be formed as an integral part of the bracket 17. The bracket is, of course, firmly secured to the cover 14. A valve stem 18 is provided and has its lower portion fitted in and suitably secured to the valve 8 above its vent port 13. The upwardly projecting portion of the stem 18 is threaded and has threaded thereon upper and lower nuts or abutments designated at 19 and 20. The nuts 19 and 20 may be provided with lock screws 21 and 22 to releasably secure them in any position at which they may be adjusted to the stem. By loosening the lock screws and turning the nuts in one direction or another, their position along the valve stem may be changed.

In the lowermost position of the valve which is desired when the burner is of the high fire and low fire type, the nut 20 rests against the upper end of the sleeve 16, the sleeve then serving as a stop.

The upward movement of the valve is limited by a cross pin 23 which is connected to the body of the valve and engageable with a stop 24 provided on the cover.

- 5 The valve may be conveniently held against turning by means of a cross pin 25, the ends of which project beyond the periphery of the valve and are a working fit in vertical slots 26 provided in diametrically opposite portions of the sleeve 16.
- 10 The vertical leg or portion 17' of the bracket 17 has the frame plates 27 of the laminated core of an electro-magnet designated generally at E, secured thereto by means of screws 29. One leg of the core supports the electro-magnetic winding 30. An armature 31 is pivotally connected as at 32 to extensions of the frame plates 27 at their upper corners. An operating lever designated generally at 33 has a downturned end 34 fastened to the outer side of the armature 31.
- 15 The lever extends over the electro-magnet and supporting bracket 17 and at its end remote from the magnet is provided with extensions 35 and 36 which have yokes 37 and 38 provided thereon. By having two yoked extensions the device is adapted to operate two outlet valves. In some instances, only one outlet valve is required and as they are identical only one is shown. In the construction illustrated, the yoke 38 embraces the stem 18 in between the nuts or abutments 19 and 20. The 20 parts are so proportional and arranged that when the magnet E is de-energized the weight of the lever 33 disengages its yoke 38 from the nut or abutment 19 and allows the valve to drop down until the lower nut 20 engages the upper end of the guide 16. This is the low fire position of the valve. When the magnet is energized the armature 31 is swung over to the position shown in Figure 1, thereby rotating the lever 33 in a counterclockwise direction and causing its yoke 38 to 25 engage the upper nut or abutment 19 and elevate the valve to its high fire position. The extent to which the lever is effective to elevate or open the valve is determined by the adjustment of the nut 21. Thus, the high fire can be adjusted from high capacity down to almost nothing. The 30 low flame can also be adjusted by adjusting the lower nut 20.

The bracket 17 may be provided with a second vertically extending web 39 to support an insulating panel 40 on which binding posts 42 are provided to receive the power supply lines 43. The terminals of the winding 30 are connected to these binding posts by wires 44. With this construction both high and low flame adjustments are had 35 simply by adjusting two nuts or abutments on a single valve stem. Only a single lever is required and yet the electro-magnet exercises complete control over the device.

While I have shown and described one construction in which the invention may be advantageously embodied, it is to be understood that this construction has been selected merely for the purpose of example and illustration and that various changes in the size, shape and arrangement of the parts may be made without departing from the spirit of the invention or the scope of the subjoined claims.

The invention claimed is:

1. An oil control valve comprising a casing having an oil supply chamber provided with an outlet, a valve seat in said outlet, a metering valve having its lower end coacting with said valve seat to regulate flow therewith, a cover for the casing having an opening, a guide for the valve 70 associated with the opening, said valve having a

stem projecting above said guide, spaced abutments adjustably secured to the stem whereby the position of the abutments longitudinally of the stem may be varied, means for releasably securing the abutments in adjusted position, an electro-magnet mounted on the cover and having a swingable armature, and an operating lever secured to the armature and having one end co-operable with one of the said abutments to raise the valve when the magnet is energized, the other abutment coacting with said guide to limit the closing of the valve when the magnet is de-energized.

2. An oil control valve comprising a casing having an oil supply chamber provided with an outlet, a valve seat in said outlet, a metering valve having its lower end coacting with said valve seat to regulate flow therewith, a cover for the casing having an opening, a guide for the valve associated with the opening, said valve having a threaded stem projecting above said guide, a pair of nuts threaded on said stem, means for releasably securing the nuts in adjusted position, a bracket mounted on the cover, an electro-magnet comprising a core having frame plates fastened to the bracket, a winding on the core, an armature pivoted to the frame plates of the core, and a lever fixed to the armature and having a yoke embracing said stem between said nuts and co-operable with one of said nuts to elevate the 20 valve when the magnet is energized, the other of said nuts coacting with the guide to limit the closing movement of the valve.

3. An oil control valve comprising a casing having an oil supply chamber provided with an outlet, a valve seat in said outlet, a metering valve having its lower end coacting with said valve seat to regulate flow therewith, a cover for the valve, said cover having an opening, said valve having a stem projecting through the opening, a nut threaded on the stem, means for releasably securing the nut in adjusted position, a swingable lever co-operable with the nut to elevate the valve, means for swinging the lever upwardly, and means for limiting the lowering movement of the valve when the lever is allowed to swing downwardly, said lever being free to swing after the lowering movement of said valve has been limited by said last named means.

4. An oil control valve comprising a casing having an oil supply chamber provided with an outlet, a valve for regulating flow through the outlet, said valve having a stem, a pair of nuts threaded on the stem, an electro-magnet having a swingable armature and a single lever connected to said armature and co-operable with one of the nuts to effect opening of the valve when the electro-magnet is energized, and a stop engageable with the other nut to control the position of the valve when the electro-magnet is de-energized.

5. An oil control means comprising a casing having an oil supply chamber provided with an outlet, a metering valve coacting with the outlet to regulate flow therethrough, a cover for the valve having an opening, a guide for the valve, supported on the cover and associated with the opening, said valve having a stem projecting above the guide, an electro-magnet mounted on said cover, a lever actuated by said magnet and co-operable with the stem to effect opening of the valve 70 when the magnet is energized, and means adjustable on the stem and co-operable with said guide for limiting the closing movement of the valve.

6. An oil control valve comprising a casing having an oil supply chamber provided with an

outlet, a valve for regulating flow through the outlet, said valve having a stem, spaced abutments adjustably secured to the stem whereby the position of the abutments longitudinally of the stem may be varied, an electromagnet having a swingable armature, a single lever secured to the armature and having one end cooperable with

one of said abutments to raise the valve when the magnet is energized, and a stop engageable with the other abutment to control the position of the valve when the electromagnet is de-energized.

ROY W. JOHNSON.
